We claim the ornamental design for a TV screen display with transitional graphical user interface, as shown and described.

DESCRIPTION

FIG. 1 is a front view of the first image in the sequence for the present design showing our new design;

FIG. 2 is a second image thereof;

FIG. 3 is a third image thereof;

FIG. 4 is a fourth image thereof; and,

FIG. 5 is a fifth image thereof.

The subject matter in this patent or application includes images that transition between the figures. The process or period in which the images move forms no part of the claimed design.

The dot-dash broken lines represent a boundary of the claimed design. The dash-dash broken lines depict unclaimed environment. The broken lines form no part of the claimed design.
